METHOD OF MAKING PENS

John A. Shea, Jersey City, N. J.

Application March 21, 1940, Serial No. 325,105

3 Claims. (Cl. 113—32)

This invention relates to the manufacture of fountain pen nibs by means of a process enabling the complete pen to be made from a blank strip of metal in a particular manner without the hand of man touching it. More particularly, the object of this invention is to complete the writing tip of the pen in final writing condition while it is still an integral part of the metal strip, by operating upon only one lateral edge of the strip, the entire remaining portion of the strip acting to support and resist the forces to which said lateral edge has been subjected. Generally speaking, sufficient metal is first cut out along one edge of the blank strip to leave remaining a pen nib from tip to shoulder only and then the tip only of the nib is progressively operated upon to completion of the tip, while at the same time other successive tips are being progressively formed to completion simultaneously with the first tip.

It will be recognized that as the writing tip of a fountain pen is of very small dimension, and because it must be constructed so as to function as part of an automatic writing instrument, very fine and delicate work is absolutely essential. This is especially true when a wing tip or other type of thickened writing tip is utilized. In order to effect this very delicate work of manufacturing the tip it is necessary that the tips be well supported to prevent wobbling or shifting during such manufacture. This entirely new conception of completing all the operations on the tip of the pen while it is still an integral part of the strip of metal from which the pen is to be made, gives the very vital and necessary support to the tip while it is being made, and it is because of this that, for the first time, a completed fountain pen tip has been made from a blank strip of metal without the hand of man touching it.

The invention will be more fully described hereinafter, embodiments thereof shown in the drawings, and the invention will be finally pointed out in the claims.

In the accompanying drawings:

Figure 1 is a plan view of a strip showing the various step by step progressive steps to form a complete pen tip while on the metal strip, and also to form a complete pen;

Figure 2 is a similar view showing the relationship of the manufacturing devices which operate upon the edge of the metal strip or upon the points of the nibs, said devices being shown as arranged to operate upon the nib tips only;

Figure 3 is a side view of the blank of metal

strip shown in Figure 2 with the devices arranged in respect thereto;

Figure 4 is a plan view of the initial nib tip with the wings in a plane and made in accordance with station A;

Figure 4a is a transverse section of Figure 4;

Figure 5 shows the nib tips of which the corners and edges have been smoothed and hardened by means of the device indicated by station B, the corners and edges of Figure 4 condition being removed;

Figure 6 is a vertical central section of the winged tip brought into a V-shaped formation by the device of station C, the apex of the V being indented and hardened by compression at its face and being rounded and hardened at the back;

Figure 7 is a vertical section partly in elevation looking from the front ends of the tips, showing the V-shaped formation of Figure 6 brought into parallel relationship by means of the device of station D and the tip having been compressed, its volume having been reduced and the back having been indented;

Figure 8 is a side elevation of Figure 7 showing how the tip has been formed for writing either on the face surfaces as indicated on Figure 7, or on the back also, since the back of the tip extends below plane of the back of the nib;

Figure 9 is a plan view of the winged tips after the slitting operation by shearing has been completed whereby the winged tips are separated from each other and caused to take an askew position, as shown in Figure 10, this operation taking place by station E;

Figure 10 is a front view of Figure 9;

Figure 11 is a top view of the winged tips after the winged tips have been brought together at their tip ends, whereby the slit has been controlled in respect to its width, the slit being now in curved form resulting from the operation of station F;

Figure 12 is a front view of Figure 11 showing how the tips are nearer to each other than in the form of Figure 10;

Figure 13 is an end or front view of the final pen when evened up and a plan view thereof might look like Figure 11 and a side view look like Figure 8, and

Figure 14 is a plan view of the finished pen shown in Figure 13, the slit being curved about as shown in Figure 11 but being hidden by the positioning of the wings and made by station G.

Similar characters of reference indicate corresponding parts throughout the various views.

The metal of the pen may be of a very hard and brittle nature such as stainless steel, containing about 4% of molybdenum.

Referring to the drawings, and particularly to Figures 3 to 12, the various essential formations of a wing tip pen made by an automatic machine are shown in Figures 4 to 12, and these are the various intermittent results of the operations of station A to station F in Figure 3.

The first operation at the station A is to cut out of the metal strip a V-shaped cut 15, whereby nib portions 16 remain integral with the blank strip; the well known pierce holes 17 being provided in the blank prior to this first operation. The blank is also provided with alignment holes 18 on the opposite edge of the blank strip 20, these alignment holes 18 being for the purpose of aligning with suitable devices in the stations A to G. As a result of the operation of the station A as just described, wings 21 and 22 are formed at the end of the nib 16 at the tip thereof, and these wings and the nib 16 are in the same plane, they have the sharp and rough corners and edges such as result from cutting out of the metal strip, a wing tip shape, a transverse section of Figure 4 would show a rectangular shape. The strip is then moved by a step by step movement, so as to move this flat winged tip end shown in Figure 4 to the station B. The device here located operates to smooth the corners and edges of the winged tip, and at the same time hardens the same and particularly its contour, the smooth and hardened contour being indicated by the lines 23 in Figure 5. This hardened tip with the wings in a flat common plane, is then moved by the next step by step operation of the blank strip over to the station C where the tip is shaped into a V formation with a hardened rounded bottom 24 and a scored innermost hardened top 25, as shown in Figure 6.

The next step by step movement of the blank strip 20 brings this V-shaped formation to the station D where the wings 21 and 22 of the tip are brought into parallel relationship with each other and the free but now adjacent ends brought into contact at 26, at the upper part of space 27 and the ends 35 and 36 are further hardened and smoothed.

In Figure 6 the rounded bottom or back is indicated by 24, this is shaped into the part as shown in Figure 7, namely, indicated by a rib in the mold acting upon the tip for smoothing the back of the tip. This action and the compression action upon the face ends 35 and 36, reduces the volume of the metal from that of Figure 6 to that of Figure 7, this compression bending outwardly the wings, so as to leave a lenticular space between the wings formed by the adjacent sides as indicated by 27. The side view of the sectional front end view shown in Figure 7 is shown in Figure 8 which is capable of writing front and back.

The next step by step operation of the blank strip 20 moves these adjacent tips of Figure 7 over the station E. Here a slitting action takes place which is done by shearing, the shearing extending from the free edges of the tip inwardly of the nib up to the pierce hole 17 as shown in Figure 1 by the slit 30. This shearing action causes the wings 21 and 22 to separate from each other as shown in Figure 9, and also moves the right hand tip 22 higher than the left hand one as shown in Figure 10. The strip of metal is then again moved in step action so as to bring

the tips, having the respective positions of Figures 9 and 10, over to station F.

At station F the tips 21a and 22a of the tips 21 and 22 are brought toward each other by a suitable manipulation of the metal into the form shown in Figure 11 where the wings incline toward each other and the askew position of Figure 10 is changed into the askew position of Figure 12 which is a front view of Figure 11. At the same time, in the operation of station F, the bending of the tips controls the formation of the slit 30 and its spacing and its curvature 30a as a primary control. According to the inclining of the tips in respect to each other (see Figure 11), the slit is varied but at all times spaced. The strip 20 is then moved again by the step by step action and the end of the nib, as shown in Figures 11 and 12, is brought to a station G and here the device at G acts to even the tips so that the face or top edges 35, and 36, and the back edges 37 and 38 are even with each other or in the same plane. This step, however, can be omitted, but is now only mentioned to show that during the stations A to G, the winged tip of a pen is shaped by automatic machinery by a step by step progressive action from the blank strip shown in Figure 4 to the uneven structure shown in Figure 12. Preferably the evening of this uneven structure is intended to be done in the forming stage when the pen is rounded or at completion, as shown in Figure 1 by the legend "Form pen and open slot."

I have thus described the operation of the various essential steps in the formation of a pen tip of a wing pen, which are carried out along one edge of a blank strip, namely at the tip of the nibs of that blank strip, all the rest of the blank strip being unoperated upon excepting only to the extent that parts of the device may clamp and hold the nibs or parts thereof. The nib portions and also the blank portions serve as a strengthening member for the various operations that are being exerted upon the very tips of the nibs. Having formed the essential portions, the remaining portions are to cut out the contour of the pen as shown by station H in Figure 1 to form the pen which could be done at station I of Figure 1 instead of "form pen and open slot." The pen is then cut off from the remaining strip as shown in station J of Figure 1.

It is seen that extreme hardening by compression and reduction of volume and shaping or swaging of the tip has been carried out upon an extremely hard material, while the tip is part of the nib and metal strip, such formative actions being possible only on account of the tenacity of the resistance offered by an edge of a flat strip being acted upon progressively and simultaneously.

The tips resemble a lathe ground pen. By this is meant that when an iridium pen is being made it is in a rough condition or state, and is then ground by means of hand tools worked on a lathe fed by emery and oil to smooth this roughened condition into a smooth writing instrument. In the improved steel pen hereinbefore described, a similar smooth writing surface condition is obtained by the action of the compression dies in the mold form which convert the form of Figure 6 to Figure 7. Here, a compression smoothing and swaging action takes place, with the reduction of volume of metal, as is seen from the reduced compressed size of Figure 7 compared to Figure 6.

Reference is made to my two patents,

Numbers 2,195,430, dated April 2, 1940, and 2,208,477, dated July 16, 1940, respectively, and to co-pending applications, Serial No. 321,218, filed Feb. 28, 1940, and Serial No. 321,217, filed Feb. 28, 1940, respectively, to issue on the same date herewith, and to my pending application Serial No. 357,926, filed Sept. 23, 1940.

I have described an embodiment of my invention, but it will be clear that changes may be made within the principle of the invention described, without departing from the scope of the subjoined claims.

What is claimed is:

1. In making of pens from a flat strip body of metal having parallel longitudinal sides and having spaced pierce holes and pilot holes, wherein said strip is subjected to a plurality of successive operations of dies as the strip advances step by step through the same with all the operations acting simultaneously and while the strip body is held at the pilot holes by the registration of the dies therewith, and in which said strip body at one longitudinal side thereof at one station has sufficient metal cut out to leave remaining a pen nib from tip to shoulder only in flat form in the same plane with the strip body, with said tip having lateral wings in the same plane as the nib, the extended nib being solid and integral with the strip body, the remainder of the strip body remaining longitudinally integral and unoperated upon from the shoulder to the opposite longitudinal side of the strip body; and in which while the nib still remains an integral part of the strip and the remainder of the strip from the shoulder to the opposite longitudinal side of the strip remains unoperated upon, the wings are bent along a line intermediate the same to a V shape, with the V having its apex at the face of the pen and the back of the pen being rounded opposite to the apex; the method which consists in molding said V-shaped wings to substantial parallelism and compressing the same to smooth and harden the writing surfaces of the top and bottom of the wings under reduction of volume of the wings, then shearing the metal between the wings along said apex from the tip to the pierce holes to separate the wings, and then evening the wings from any unevenness resulting from the shearing action, said pen nib operations taking place upon the extended nib at the various stations progressively from station to station but under simultaneous operation of the dies, while the pen nib extends from and is part of the strip body and before the pen body is cut from the strip body.

2. In the making of pens from a flat strip body of metal having parallel longitudinal sides and having spaced pierce holes and pilot holes, wherein said strip is subjected to a plurality of successive operations of dies as the strip advances step by step through the same with all the operations acting simultaneously and while the strip body is held at the pilot holes by the registration of the dies therewith, and in which said strip body at one longitudinal side thereof at one station has sufficient metal cut out to leave remaining a pen nib from tip to shoulder only in flat form in the same plane with the strip body, with said tip having lateral wings in the same plane as the nib, the extended nib being solid and integral with the strip body, the remainder of the strip body remaining longitudinally integral and unoperated upon from

the shoulder to the opposite longitudinal side of the strip body; and in which while the nib still remains an integral part of the strip and the remainder of the strip from the shoulder to the opposite longitudinal side of the strip remains unoperated upon, the wings are bent along a line intermediate the same to a V shape, with the V having its apex at the face of the pen and the back of the pen being rounded opposite to the apex; the method which consists in molding said V-shaped wings to substantial parallelism and compressing the same to smooth and harden the writing surfaces of the top and bottom of the wings under reduction of volume of the wings, then shearing the metal between the wings along said apex from the tip to the pierce holes to separate the wings, and then evening the wings from any unevenness resulting from the shearing action, said pen nib operations taking place upon the extended nib at the various stations progressively from station to station but under simultaneous operation of the dies, while the pen nib extends from and is part of the strip body and before the pen body is cut from the strip body.

3. In the making of pens from a flat strip body of metal having parallel longitudinal sides and having spaced pierce holes and pilot holes, wherein said strip is subjected to a plurality of successive operations of dies as the strip advances step by step through the same with all the operations acting simultaneously and while the strip body is held at the pilot holes by the registration of the dies therewith, and in which said strip body at one longitudinal side thereof at one station has sufficient metal cut out to leave remaining a pen nib from tip to shoulder only in flat form in the same plane with the strip body, with said tip having lateral wings in the same plane as the nib, the extended nib being solid and integral with the strip body, the remainder of the strip body remaining longitudinally integral and unoperated upon from the shoulder to the opposite longitudinal side of the strip body; and in which while the nib still remains an integral part of the strip and the remainder of the strip from the shoulder to the opposite longitudinal side of the strip remains unoperated upon, the wings are bent along a line intermediate the same to a V shape, with the V having its apex at the face of the pen and the back of the pen being rounded opposite to the apex; the method which consists in molding said V-shaped wings to substantial parallelism and compressing the same to smooth and harden the writing surfaces of the top and bottom of the wings under reduction of volume of the wings, then shearing the metal between the wings along said apex from the tip to the pierce holes to separate the wings, and then bending the tips laterally of each other to widen the space between the wings and contacting the tip of the wings to provide a curved slit substantially closed at the tip, said pen nib operations taking place upon the extended nib at the various stations progressively from station to station but under simultaneous operation of the dies while the pen nib extends from and is part of the strip body and before the pen body is cut from the strip body.

JOHN A. SHEA.
